(57) **CLAIM**

We claim the ornamental design of a molded fingerprint sensor structure, as shown and described.

DESCRIPTION

FIG. 1 is a perspective view of a fingerprint sensor chip with integrally molded bezels;

FIG. 2 is a front plan view of a fingerprint sensor chip with integrally molded bezels;

FIG. 3 is a left side view of a fingerprint sensor chip with integrally molded bezels;

FIG. 4 is a right side view of a fingerprint sensor chip with integrally molded bezels;

FIG. 5 is a bottom view of a fingerprint sensor chip with integrally molded bezels;

FIG. 6 is a top view of a fingerprint sensor chip with integrally molded bezels; and,

FIG. 7 is a back plan view of a fingerprint sensor chip with integrally molded bezels.
